(57) **CLAIM**

I claim the ornamental design for an electronic reader, as shown and described.

DESCRIPTION

FIG. 1 is a front perspective view of an electronic reader.

FIG. 2 is a front elevation view of the electronic reader illustrated in FIG. 1.

FIG. 3 is a rear elevation view of the electronic reader illustrated in FIG. 1.

FIG. 4 is a right elevation view of the electronic reader illustrated in FIG. 1.

FIG. 5 is a left elevation view of the electronic reader illustrated in FIG. 1.

FIG. 6 is a top plan view of the electronic reader illustrated in FIG. 1; and,

FIG. 7 is a bottom plan view of the electronic reader illustrated in FIG. 1.

The portions of the electronic reader in broken lines are shown for illustrative purposes only and form no part of the claimed design.
